UNITED STATES PATENT OFFICE.

HARRISON CADY, OF BROOKLYN, NEW YORK, ASSIGNOR TO THE TIN DECORATING COMPANY OF BALTIMORE, OF BALTIMORE, MARYLAND, A CORPORATION OF NEW JERSEY.

DESIGN FOR A BOX OR SIMILAR ARTICLE OF MANUFACTURE.

Application filed April 5, 1922. Serial No. 1,559. Term of patent 7 years.

To all whom it may concern:

Be it known that I, HARRISON CADY, a citizen of the United States, residing at Brooklyn, county of Kings, city and State of New York, have invented a new, original, and ornamental Design for a Box or Similar Article of Manufacture, of which the following is a specification, reference being had to the accompanying drawing, forming a part thereof, wherein:

Figure 1 is a perspective view of my ornamental design as applied to a box structure, and

The design is shown as embodied in or applied to a box part, but I contemplate that the same may be also embodied in or applied to other analogous articles of manufacture.

What I claim is:

The ornamental design for a box or similar article of manufacture substantially as shown and described.

HARRISON CADY.
